UNITED STATES PATENT OFFICE.

ROBERT S. MURPHY, OF DETROIT, MICHIGAN, ASSIGNOR TO THE ELECTROGRAPH COMPANY, OF DETROIT, MICHIGAN, A CORPORATION OF MICHIGAN.

STAMP-AFFIXING APPARATUS.

Application filed March 29, 1926. Serial No. 98,155.

My invention relates to stamp affixing and sealing apparatus. And an object of my improvements is to provide an improved apparatus for placing stamps upon folders and thereby securing the detached edges of the folder together for mailing. I secure this object in the apparatus illustrated in the accompanying drawings in which:

Figure 1, is a plan view of a stamp affixing machine with apparatus embodying my invention attached thereto.

Figure 2, is a side elevation to an enlarged scale of a portion of the machine and apparatus shown in Fig. 1.

Figure 3, is a section on the line III, III, of Fig. 2.

Figure 4, is a detailed section in the plane indicated by the line IV, IV Fig. 2.

Figure 5, is a section on the line V. V. Fig. 1.

Figure 6, is a perspective view of the stamp turning shoe and its attaching parts.

Figure 7, is a perspective view looking from beneath Fig. 6.

Figure 8, is a perspective view of the rollers, carrier and guides therefor, by which rollers the stamp upon the folder is held during the turning over of the protruding portion thereof.

Figure 9^a, is a perspective view of a portion of the edge of a folder with the stamp affixed ready to be turned over upon the other outer surface of the folder to secure the detached edges of the folder together.

Figure 9, is a detailed sectional view showing the stamp and adjacent parts of the apparatus when the stamps are just beginning to be turned over.

Figure 10, is a view similar to Figure 9 the stamp being turned to a greater degree.

Figure 11, is a view similar to Figures 9 and 10, the stamp being completely turned over.

Figure 12, is a detailed section in the plane XII—XII, Fig. 8.

Figure 13, is a perspective view of the folder with the stamp affixed thereto in position to hold the detached edges of the folder together for mailing.

I have represented my improved apparatus in connection with a stamp affixing machine of the type known as Mail-O-Meter, and this is adjusted to affix the stamp to one surface of the folder at the center,

a portion of the stamp protruding beyond

the folder where the edges thereof are detached, as described in the co-pending application of Reed Adams, for a method and apparatus for affixing stamps on mailing matter, Serial No. 733,332, which on the 7th day of February, 1928, resulted in United States Letters Patent Number 1,658,218.

a—a, b—b, are the feeding rolls of the machine and *d* is the stacker. *abc*, (Fig. 4) are the gear wheels through which the rollers *a, b*, and *c* are actuated. *e—e*, are the guides for the folder and *f* is the receiving table for the stamped folders.

c—c, are rollers for fixing the stamp in its turned over position.

The folder is fed to the machine at the left of Fig. 1, with the edges that are detached upward has the stamp affixed thereto in the usual way, except that about half of the stamp protrudes beyond the upper edge of the folder, passes between the pairs of rollers *a, b*, and *c* and is stacked upon the table *f*. While thus passing through the machine the protruding portion of the stamp is turned over upon the other surface of the folder and is caused to adhere thereto so as to join said edges and seal the folder by an apparatus described as follows:

g, is a shoe made of sheet metal, or other suitable material placed, with its axis approximately horizontal, between the pairs of rollers *a—a*, and *b—b*. The shoe *g*, is approximately conical in shape with its lower portion open, as illustrated in Figures 6 and 7. The larger end of the shoe is adjacent to the rollers *a—a* and positioned to receive and engage the protruding of the stamp, as shown in Fig. 9.

n and *n²* are stationary portions of the machine frame,

g², is a Z-shaped piece of spring metal secured to the smaller end of the shoe *g* at one end and adjustably secured in a slot *g³* in the frame part *n* by a screw *g⁶*.

g⁴, is an elastic arm one end of which is secured to the larger end of the shoe *g* and the other end is adjustably attached to the frame part *n²*, by a screw *g⁶* passing through the slot *g⁵*.

h, is a socket piece fixed to the frame of the machine with its open end just below the shoe *g*.

h², h², are the upper and lower sides of the socket *h*.

j, is a carrier having a vertical inner por-

tion j^2 and horizontal upper and lower portions j^3-j^3 . (Fig. 8.)

j^4 , is a series of rollers pivoted vertically between the upper and lower portions j^3 of the carrier j . hj , are springs interposed between the back of the socket piece h and the rear of the carrier j and adapted to press said carrier outward and the rollers against the stamps on the passing folder. The rollers j^4 are of such a size that one is always in engagement with the stamp when it is passing through the shoe g and thereby the attached portion of the stamp is held in contact with the folder so that the turning over 15 of the protruding portion shall not detach the attached portion.

The operation of the above described apparatus is as follows:

The folders are fed to the machine from 20 the left of Fig. 1, have the stamps affixed thereto with their upper ends protruding above the edge of the folder, as shown in Figure 9^a and pass between the rollers $a-a$ and are fed between a guide e and the rollers 25 j^4 . During which passage the protruding portion of the stamp is turned over by the shoe g , as shown in Figures 9, 10, and 11 and is fixed to both surfaces of the folder m securing the detached edges together, as 30 shown in Fig. 13. The folders are then fed forward through and between the rollers $b-b$ and $c-c$ which causes the turned over portion of the stamp to adhere firmly to the opposite surface of the folder.

What I claim is:

1. In combination with a stamping machine adapted to affix a stamp to mail matter with a portion of the stamp protruding beyond the edge thereof and to cause the mail matter to be carried therethrough, an 40 apparatus interposed in the line of travel of said mail matter through the machine, adapted to turn the protruding portion of the stamp over upon the surface of the mail matter and mechanical means for holding 45 the portion of the stamp attached to the folder in contact therewith while the protruding portion of the stamp is being turned over.

2. In combination with a stamping machine adapted to affix a stamp to mail matter with a portion of the stamp protruding beyond the edge thereof and to cause the mail matter to be carried therethrough, an 50 apparatus interposed in the line of travel of said mail matter through the machine, adapted to turn the protruding portion of the stamp over upon the surface of the mail matter and mechanical means for holding 55 the portion of the stamp attached to the folder in contact therewith while the protruding portion of the stamp is being turned over, said mechanical means consisting of a series of small rollers yieldingly pressing 60 against the detached portion of the stamp.

In testimony whereof, I sign this specification.

ROBERT S. MURPHY.
